UNITED STATES PATENT OFFICE.

OTTO GASAU, OF BROOKLYN, NEW YORK.

MATTRESS-FRAME.

1,149,360.

Specification of Letters Patent. Patented Aug. 10, 1915.

Application filed February 24, 1913. Serial No. 750,057.

To all whom it may concern:

Be it known that I, OTTO GASAU, a citizen of the United States, residing at Brooklyn, in the county of Kings and State of New York, have invented certain new and useful Improvements in Mattress-Frames, of which the following is a specification.

This invention has to do with spring or mattress frames, it more particularly relating to the corner brackets thereof by means of which the frames are supported upon the frame or side bars of the bedstead, the object of the invention being to provide an improved corner bracket or supporting means for the spring or mattress frame which is capable of adjustment so as to enable the spring or mattress frame to be used with varying widths of bed frames and which is also effective to interlock the mattress frame with the bed frame.

A further object of the invention is the provision of an improved mattress frame attachment in the form of a corner bracket which is simple in its construction, effective in use and inexpensive to manufacture, and by the use of which the mattress frame may fit varying widths of bed frames and be so interlocked therewith that movement of the mattress frame lengthwise of the bed frame is prevented.

It is well known in practice that the bedstead frames of various manufacturers differ in width, and it is also well known that weather conditions have considerable to do with varying the width of the metallic bed frames, so that it is desirable that the mattress frame shall have shiftable or adjustable means whereby it will fit within reasonable limits the varying sizes of bed frames.

It is also well known that mattress frames or spring mattresses warp in transportation as well as in use, so that when applied to the bed frame they frequently rock by reason of the fact that one or more of the corners do not rest upon the side bars as they should. By reason of the present improvement, however, this rocking of the mattress frame is avoided because the mattress frame will be interlocked and clamped at all four corners on the side bars, so that each corner will equally bear upon its side bar and be prevented from rising above the side bar by warpage or other reasons, and thus any rocking movement of the mattress and the consequent annoyance and rattle of the

spring mattress when being sat or slept upon is entirely avoided.

The present invention is therefore an improvement in part upon my prior Patent No. 1,035,571, dated August 13, 1912.

In the drawings accompanying and forming part of this specification, Figure 1 is a perspective view of a bedstead and spring or mattress frame supported thereon; Fig. 2 is a detail view of one of these improved corner brackets; Fig. 3 is a detail view of a somewhat modified form thereof; and Fig. 4 is a detail view of the adjustable member carried by the bracket.

Similar characters of reference indicate corresponding parts in the different figures of the drawings.

The mattress frame 2 comprises usually a pair of transverse or crosswise extending members or angle bars 3 for supporting a suitable spring fabric 16 under tension connected to what is known as corner brackets 4, which corner brackets are usually formed to receive side bars 5. In the present instance each of these corner brackets is provided with a guideway 6 extending transversely of the bracket at the end of the socket portion 7 which receives the end of the side bar, this guideway being in the form of a casing closed on all four of its sides but open at its ends. In this guideway casing is located the adjustable member, which consists of an adjustable slotted bar 8 through the slot of which a bolt projects having a threaded end for the reception of a nut 9 adapted to fit in an angular opening 10 of the guideway casing and a wing nut 11 on the end. By clamping the wing nut tightly the adjustable bar is held in its adjusted position. The end of this bar is formed with a projecting recessed portion 12 forming an overlapping projecting portion 13 and an underlapping projecting portion 14 shorter than the overlapping portion, the projecting overlapping portion 13 being adapted to rest on the top of the side bar of the bedstead and the underlapping portion adapted to extend under the edge of the same, whereby the edge of the side bar will be received within the recess of this adjustable member so that when the locking nuts are clamped the mattress frame will be held against movement by reason of the reception of the side bar within the recessed end of each adjustable member.

By adjusting the adjustable members to tightly engage the side bars of the bedstead, the mattress frame will be held in place and will not rock or move lengthwise of the bed frame. The side bars 5 are interlocked with the mattress frame 2 by the corner brackets 4, so that the mattress frame will not move laterally or longitudinally of the bed frame. The side bars 5 are interlocked with the mattress frame 2 by the corner brackets 4, so that the mattress frame will not move laterally or longitudinally of the bed frame.

gage the side bars in the manner described 5 movement of the mattress frame lengthwise or crosswise of the bedstead will be prevented in a manner which will be readily understood. Moreover, by reason of the interlocking of the adjustable members of the corner brackets with the side bars the lifting of the mattress frame from off the bedstead frame is also prevented until the side bars are released from the adjustable members.

The adjustable sliding bars or members are so formed that they may be readily reversed if this should be necessary for any purpose; that is to say, they are interchangeable one with another. In the form shown 15 in Fig. 3 the adjustable interlocking member or bar of the bracket is shown located below a laterally projecting member 15, which may be used to support the mattress 20 frame at each corner on the side rail or bar of the bedstead if for any purpose it is desired to remove the adjustable bar. In other words, by removing the adjustable bar the forward end of which is located under the 25 side extension of the bracket, each bracket may be used in the ordinary manner for supporting the mattress frame at its corners upon the side rails. It will be observed that the corner brackets are so formed that 30 the clamping nuts are readily accessible.

I claim as my invention:

1. A mattress frame having corner brackets 35 each having a closed guideway casing except at its ends, a slotted adjustable slideable locking bar therein, and means for clamping said bar in said casing, said bar having means at its end for interlocking it with the side rail of a bedstead.

40 2. A mattress frame having corner brackets each provided with a lateral extension formed to rest upon the side rail of a bedstead and having below said extension an adjustable slideable locking bar adapted to engage the side rail of a bedstead.

Copies of this patent may be obtained for five cents each, by addressing the "Commissioner of Patents, Washington, D. C."

3. A mattress frame having corner brackets 45 each provided with a lateral extension formed to rest upon the side rail of a bedstead and having below said extension an adjustable slideable locking bar adapted to engage the side rail of a bedstead, and means 50 for clamping said bar in any of its adjusted positions.

4. A mattress frame having corner brackets each provided with a lateral extension 55 formed to rest upon the side rail of a bedstead and having below said extension an adjustable slideable locking bar adapted to engage the side rail of a bedstead, and means for clamping said bar in any of its adjusted positions, said bar having its end formed 60 to interlock with said side rail.

5. A mattress frame having corner brackets each provided with a lateral extension 65 formed to rest upon the side rail of a bedstead and having below said extension an adjustable slideable locking bar adapted to engage the side rail of a bedstead, and means for clamping said bar in any of its adjusted positions, said bar having its end provided with a pair of projections adapted 70 to overlap and underlap the side rail and forming a recess for the reception of said side rail.

6. A riser corner bracket for a mattress 75 frame having a closed guideway casing except at its ends, a slotted adjustable slideable locking bar therein, and means for clamping said bar in said casing, said bar having means at its end for interlocking it with the side-rail of a bedstead.

Signed at New York, in the county of 80 Queens, N. Y., this 20th day of February, 1913.

OTTO GASAU.
